MASS SPECTROMETRY

Robert V. Langmuir, Schenectady, N. Y., assignor
to Consolidated Engineering Corporation,
Pasadena, Calif., a corporation of California

Application July 15, 1943, Serial No. 494,807

4 Claims. (Cl. 73—18)

This invention is concerned with mass spectrometers and provides improvements which greatly facilitate the interpretation of spectra obtained with such instruments.

A mass spectrometer is an apparatus for sorting ions according to the ratio of the mass of the ion to the charge that it carries, (this ratio being referred to hereinafter as "specific mass") and can be employed for various purposes including qualitative and quantitative analyses of mixtures containing different kinds of molecules (for example a mixture of hydrocarbons), determination of isotope ratios, etc. It may include means such as an ionization chamber in which molecules of the mixture to be analyzed are converted into ions, means such as an analyzer tube in which a beam of the ions is separated (under the influence of an electric or magnetic field or both) into a plurality of diverging beams of ions of different specific mass (the ions of the same specific mass being included in a single beam), an ion collector, means for bringing the several beams successively into contact with the collector (which means is referred to hereinafter as the "beam sweeper") and means for indicating separately (and preferably recording) the currents collected from the several beams.

The record thus obtained represents the "mass spectrum." It may take any one of several forms, but conveniently is a graph on which the magnitudes of the currents corresponding to the several collected ion beams are represented by the heights of a series of peaks projecting from the abscissa axis. Such a record can be produced on a laterally moving sheet, for example a photographic paper by a recording galvanometer or the like. For some purposes, such a recorded mass spectrum is entirely adequate, but in other cases, for example in the quantitative analysis of a mixture of hydrocarbons containing a number of different kinds of molecules, some of which upon being bombarded with ionizing particles crack to form a plurality of different kinds of ions, it is necessary to determine the specific mass of the ions to which each peak corresponds.

In accordance with my invention, the interpretation of a mass spectrum is facilitated by indicating in a coordinated manner and preferably simultaneously with the indication of the peaks (ion currents), the specific masses of the ions to which the respective peaks (currents) correspond. Thus my invention contemplates, in a mass spectrometer, the combination which comprises means for marking on a record a series of peaks representing the relative abundance of ions of dif-

ferent specific mass separated from each other in the spectrometer and means for indicating simultaneously with the marking (and preferably on the same record adjacent the respective peaks) the specific masses of the ions to which said peaks correspond.

In one form of the apparatus of my invention the specific mass indicator is operatively connected with the beam sweeper and is actuated by it. For example, a spectrometer constructed in accordance with my invention may comprise an ionization chamber or the like wherein molecules of a mixture are bombarded with an electron beam and converted into ions, an ion propelling device such as a plurality of spaced electrodes which impress upon the ions a potential to propel them through an analyzer or sorting chamber in which the ion beams are separated, i. e., caused to diverge from each other, an ion collector, a beam sweeper for causing the separated ion beams to sweep successively over and impinge upon the collector, a recording galvanometer connected to the collector to record the currents collected from successive beams separately on a chart, and a specific mass indicator operatively associated with the beam sweeper and actuated in response to it for marking on the chart successively during the recording of the currents and adjacent the respective peak positions the specific mass of ions to which each current corresponds.

In one form of my apparatus the beam sweeper automatically and gradually alters either the potential impressed between the ion propelling electrodes or the magnetic field, thus causing the paths of the beams propelled through the analyzer to change sufficiently to sweep the beams successively over the collector. The "specific mass" indicator is connected in a circuit with the beam sweeper and the propelling electrodes, and the change in potential in this circuit actuates the mass indicator. For example, the mass indicator may be a galvanometer calibrated in terms of the ion masses or it may be a vacuum tube circuit which is tripped at intervals at successive values of ion accelerating potential, means being provided to mark the spectrogram each time the circuit trips. In this way the beam sweeper and the mass indicator are synchronized and the peaks on the spectrogram correlated with the specific masses of ions to which they correspond.

The foregoing and other features of my invention will be more thoroughly understood in the light of the following detailed description taken in conjunction with the accompanying drawings in which:

Fig. 1 is a diagram of a mass spectrometer provided with a mass marker controlled by a beam sweeper and adapted to identify the various peaks corresponding to various ion beams on a recorded mass spectrogram.

Fig. 2 is a wiring diagram of a preferred form of mass marker of my invention applied to a mass spectrometer and actuated by a beam sweeper of the type described and claimed in the co-pending application Serial 499,055, filed August 18, 1943 by Raymond C. Olesen;

Fig. 3 is a graph illustrating the manner in which the ion accelerating voltage decays during the recording of the mass spectrogram; and

Fig. 4 is a graph illustrating the grid bias of the mass marker circuit and its utilization to indicate specific mass in correlation with the peaks on the mass spectrogram.

Referring now to Fig. 1, it will be observed that the apparatus comprises an ionization chamber connected to a tubular semi-circular analyzer both adapted to be maintained under high vacuum, for example, by enclosure in an evacuated envelope (not shown). A sample of gas to be analyzed is admitted to the ionization chamber through a gas sample inlet conduit and the molecules of the gas are bombarded in the chamber by an electron beam, so that they are ionized. The ions are forced by electrical potential out of the ionization chamber and through the adjacent analyzer. This is accomplished by impressing a potential between a pusher electrode P disposed in the ionization chamber and a first propelling electrode E₁, which forms one wall of the chamber. Thus an electrical potential is impressed across the region through which the electron beam passes and ions formed in this region are pushed through an exit slit S₁ in the first propelling electrode. The ions are accelerated further by voltages of higher potential impressed between the electrode E₁ and a second propelling electrode E₂, which has a slit S₂ matching that in the first electrode. The two slits act as a collimator.

The ionization chamber and the analyzer are both mounted between the poles of a large electromagnet (not shown) with the result that the heterogeneous beam of ions issuing into the analyzer through the slit S₂ pursues a curved path toward an exit slit S₃ at the far end of the analyzer tube. The magnetic field acts upon the ions and separates them in accordance with their specific masses into a plurality of separated diverging beams B₁, B₂, B₃, B₄, B₅ etc., each composed of ions of a different given specific mass. By varying the strength of the magnetic field or the accelerating potentials, or both, the radii of curvature of the several beams may be altered simultaneously with the result that the beams are swept successively over the exit slit S₃. As a beam passes through the exit slit it impinges on an ion collector. The current carried by the beam is thus discharged. This current is amplified and recorded as a series of peaks on a moving record or spectrogram in an automatic amplifier and recording system. Automatic recorders for such mass spectrograms are described in a co-pending application Serial No. 437,922 filed April 6, 1942, by Edmund E. Hoskins and myself, and in my co-pending application Serial No. 444,491, filed May 25, 1942.

Since the ion beams that are separated from each other in the analyzer are spaced substantially apart at the far end of the analyzer adjacent the ion collector, the collected currents appear on the spectrogram as a series of peaks

separated by blank spaces. Each peak corresponds to a specific mass, but it is difficult to identify these masses without the mass marker of my invention.

5 To consider the balance of the apparatus of Fig. 1, it will be observed that it comprises a high voltage D. C. potential supply which is connected to the ion accelerating electrodes P, E₁ and E₂ of the spectrometer through a beam sweeper and a potential divider. The function of the beam sweeper is to change gradually the potential applied to the ion accelerating electrodes, thereby causing the beams to move successively past the exit slit S₃. The potential divider is employed to 10 distribute a relatively small potential between the pusher electrode and the first propelling electrode, and a relatively large potential between the two propelling electrodes. A mass marker control, which will be described in greater detail herein- 15 after, is electrically coupled with the beam sweeper through the potential divider. The mass marker is provided with a marking relay and the changing accelerating potential applied to the spectrometer by the beam sweeper effectively actuates the mass marker control so that the spectrogram is marked periodically, these marks being correlated with the peaks on the spectrogram, for purposes of identifying the masses of the respective peaks.

20 In the preferred form of my apparatus, the ion accelerating voltage (which is the voltage output of the beam sweeper and hence the voltage that appears across the potential divider) decreases as an exponential function of time, this effect being produced by a beam sweeper mechanism, for example, that described and claimed in the aforementioned co-pending application Serial No. 499,- 25 055, filed August 18, 1943 by Raymond C. Olesen. Inasmuch as the "virtual" specific mass of the 30 ions being detected at any moment varies inversely as the accelerating voltage, the "virtual" specific mass of ions that may be detected at any moment during the sweep of the beams across the 35 collector increases as an exponential function of time. By "virtual" specific mass of ions, I mean a mass-to-charge ratio of ions that can follow a particular line path in the mass spectrometer, say, the path B₃ from a point of ionization to a point on the collector. I employ this relationship of 40 45 "virtual" specific mass to ion accelerating voltage in the operation of the mass marker which automatically marks the mass spectrogram at the moment that ions of a predetermined specific mass are impinging on the ion collector, thus facilitating the determination of the actual specific mass 50 55 of ions which produce a particular peak on the spectrogram.

Referring now to Fig. 2, it will be observed that 60 the mass spectrometer of Fig. 1, provided with an ionization chamber, an analyzer, an ion collector and the ion accelerating electrodes P, E₁, E₂ is connected to a high voltage direct current power source 30, through a beam sweeper 31 and a potential divider 32. Thus, the potential supplied 65 from the source 30 is split and its fractions impressed, respectively, between the electrodes P, E₁ and between the electrodes E₁, E₂. The potential divider comprises a relatively small resistance 32A followed by a relatively large resistance 32B, the 70 pusher electrode being tapped in ahead of the small resistance, the electrode E₁ being tapped in between the two resistances and the electrode E₂ being connected back to the power source through 75 relay 33.

The beam sweeper comprises a vacuum tube 31A connected across the high voltage power supply 30. The grid of this tube is connected to an RC circuit comprising a resistance 35 in parallel with a condenser 34. An auxiliary direct current power supply 36 is connected in parallel with the RC circuit, a switch 37 being connected between the resistance of the circuit and the auxiliary power supply. The beam sweeper is also provided with resistors 38, 39 connected in one side of the circuit, respectively, between the tube and the potential divider and between the power supply and the tube.

In the operation of the beam sweeper, a large negative voltage is applied to the grid and across the condenser when the switch 37 is closed. Consequently, the tube resistance is high and a high voltage is developed across it. When the switch is opened the condenser discharges with a corresponding decay in the resistance of the tube and of the voltage in the circuit, so that the voltage applied to the ion accelerating electrodes decreases gradually and brings about a sweep of the ion beams successively across the exit slit to impinge upon the collector, the result being a recording of a mass spectrogram in a series of current peaks, each corresponding to an ion beam of a given specific mass.

As indicated above, the mass marker apparatus of my invention employs a rotary stepping relay connected in series with the potential divider. The other major portions of the apparatus comprise a D. C. amplifier 40, a control relay 41, a pulsating relay 42, and a marker means 43, together with suitable power sources for separating the amplifier relays, etc.

The rotary stepping relay conveniently is the type designated by Guardian Electric Manufacturing Company as "Series R stepping relay." Such a relay comprises a rotary contact arm 44 which upon rotation may contact any one of a series of equally spaced circumferentially positioned fixed taps $T_1, T_2, T_3 \dots T_{25}$. A disc or cylinder rigidly secured to the same shaft as the arm has numbers thereon which are position beneath a pointer and become illuminated when the arm contacts the corresponding tap. Thus, as shown, the numeral 3 is illuminated on a tap indicator 45 when the rotary arm contacts tap T_3 .

The rotary relay also includes a stepping coil 46 and reset coil 47. When an electrical impulse is applied to the stepping coil, the rotary contact moves to the next tap in sequence. When current is applied to the reset coil, the rotary arm returns to the first tap position T_1 .

The direct current amplifier is of conventional design and includes a switch 67 for disconnecting its anode power supply battery 49 from its amplifier tubes 50, 51, 52. In the grid circuit there is a potentiometer 53 for determining normal grid bias. The sliding contact 53A of this potentiometer is connected directly with the rotary arm 44 of the stepping relay 33.

The grid circuit is also connected to means including a battery 70 and the pulsing relay 42 for applying a negative bias to the grid across a resistance-condenser network 54 connected between a grid leak resistor 55 and ground. This additional negative bias is applied to the grid momentarily when the contacts of the pulsing relay are closed.

The time constant of the resistance-condenser network 54 in the grid circuit of the first stage of the D. C. amplifier should be small compared

to the time interval between successive steps so that the condenser becomes completely discharged before the firing instant is reached. In this way, no appreciable residual charge remains on the condenser to affect the grid bias at the firing instant.

The control relay includes a relay coil 56 and two pairs of normally open contacts 57, 58. The control relay coil is connected in the output of the D. C. amplifier and operates to close the two pairs of contacts when the D. C. amplifier output current exceeds a predetermined level corresponding to some voltage threshold in the grid circuit. That is, when the bias on the grid of the input tube falls below a predetermined level hereinafter called the "firing threshold," the control relay is actuated and its contacts are closed.

One pair of control relay contacts 58 is connected in one side of a power line 60 which supplies power to both the stepping coil 46 of the rotary relay and the coil of the pulsing relay 42. A panel light (not shown) and the marker light 43 are connected in series with the other pair of contacts 57 of the control relay. Power is applied to both lights when the contacts of the control relay are closed.

The complete cycle of operation of the mass marker during the recording of a mass spectrogram may be understood from the following explanation:

Initially, the rotary contact is set on tap T_1 by applying power to the reset coil 47, and at the same time the beam sweep circuit output voltage is set at its maximum value by charging the condenser 35 of its R-C circuit. Initially the contacts of the control relay and the pulsing relay are open and the panel light and mass marker light are off.

The initial bias on the D. C. amplifier input tube grid circuit is equal to the voltage between the cathode of the first tube and the sliding contact 53A of the potentiometer plus the voltage between the rotary arm and ground. As long as the sum of these voltage is greater than the firing threshold, the contacts of the control relay and the pulsing relay remain open.

When recording a mass spectrogram, the switch 37 is opened in the beam sweeper circuit, thereby causing the accelerating voltage across the potential divider to decrease gradually as a function of time. As a result, beams comprising ions of different specific masses successively impinge the ion collector and produce a series of peaks on the recording medium.

The voltage between the rotary contact and ground is always a predetermined fraction of the total accelerating voltage in accordance with the amount of resistance included between the tap in contact with the rotary arm and ground. Accordingly, the total bias on the D. C. amplifier input tube grid decreases as the accelerating voltage. As soon as this total bias reaches the firing threshold, the control relay in the output of the D. C. amplifier is actuated and its contact closed.

The closing of one pair of contacts causes the panel light and the marker light to illuminate. The closing of one pair of contacts causes current to flow in the stepping relay thereby moving the rotary arm from the first tap T_1 to the second tap T_2 . Simultaneously, the closing of these contacts causes current to flow in the coil of the pulsing relay 42. When the contacts of this relay are closed, a negative pulse is applied to the D. C. amplifier input tube grid thereby causing a sharp decrease in the D. C. amplifier output

Table

Tap	"Virtual" specific mass	Recording time
1	10	0
2	14	1.45
3	18	2.55
4	24	3.8
5	28	4.45
10	32	5.02
6	38	5.77
7	42	6.21
8	46	6.60
9		etc.

current and opening the contact of the control relay. Hence, the control relay contacts are closed only momentarily.

The closing of the other pair of contacts 51 of the control relay produces a momentary illumination of the panel light and the marker light. The flash of light on the panel light indicates to the operator the moment switching occurs. When the marker light flashes, it exposes the light-sensitive recording medium momentarily, thereby producing on the mass spectrogram an indication corresponding to a predetermined value of accelerating voltage and hence a predetermined value of "virtual" specific mass.

It should be noted that the fraction of the accelerating voltage that is included in the grid bias is greater when the rotary contact is on tap T_2 than when it is on tap T_1 . Accordingly, the contacts of the control relay remain open until the grid bias again reaches the firing threshold. At this time, the control relay closes again, making another mark on the mass spectrogram and moving the rotary arm to tap T_3 .

This sequence of events is repeated cyclically to produce a series of marks on the mass spectrogram corresponding to each tap $T_1, T_2 \dots T_{25}$, and adjacent the respective peaks.

It can be shown that if the "virtual" specific mass is an inverse function of the accelerating voltage, the "virtual" specific mass which may be recorded at the instant of firing while the rotary arm is on any of the taps $T_1, T_2 \dots T_{25}$, is proportional to the value of the total resistance connected between that tap and ground. If for example, it is desired to place marks on the mass spectrogram at points corresponding to ions having specific masses of 10, 14, 18, 24, 28, 32, 38, 42, 46, etc., when the rotary arm is in contact with taps $T_1, T_2, T_3, T_4, T_5, T_6, T_7, T_8, T_9$, etc., respectively, the values of the resistance between each of said taps and ground should be in the proportions 10, 14, 18, 24, 28, 32, 38, 42, 46, etc., respectively. If the sliding contact of the D. C. amplifier is set to yield a suitable firing threshold for any one of these masses, this same firing threshold will cause the mass marker to operate properly for each of the other specific masses.

The manner in which the total grid voltage applied to the first tube of the D. C. amplifier changes as a function of time during the recording of a mass spectrogram, when the ion accelerating voltage decays exponentially, may be understood from the following explanation taken in conjunction with Figs. 3 and 4.

When the accelerating voltage decays exponentially, a straight line may be obtained by plotting the logarithm of the specific mass as ordinate against time, as abscissa. Such a relationship is indicated by the graph plotted in Fig. 3. In this graph the numbers 10, 14, 18, etc., represent the values of specific mass for which it is desired to produce marks on the mass spectrogram. On the right side of the vertical axis the corresponding tap numbers are given 1, 2, 3, etc. If the accelerating voltage is initially at a value suitable for the detection of ions of specific mass 10 at the ion collector, and the voltage decays at a rate corresponding to the slope of the straight line in Fig. 3, ions of specific mass 14, 18, etc., will be recorded at the corresponding times represented by the corresponding abscissa of points on the line. Thus, the time at which the ions in question are impinging the collector are given by the values in the following table:

If the initial bias on the input tube of the D. C. amplifier has just exceeded the firing threshold, while the rotary contact was on tap T_1 , the system will fire as soon as the ion accelerating voltage begins to decay. Then the mass marker operates and makes an indication on the mass spectrogram directly above the point where ions of specific mass 10 may produce a peak. Simultaneously, the rotary arm moves to tap T_2 , thereby increasing the grid bias to a new value as shown in Fig. 4. The grid bias then decreases along a curve marked E_1 until it reaches the firing threshold. At this moment, a new mark is made on the mass spectrogram directly above a peak corresponding to the amount of any ions of specific mass 14 being recorded, and the rotary arm of the rotary relay moves to tap T_3 . Again the grid bias increases and then gradually decays along the curve E_2 until it again reaches the firing threshold. This process is repeated sequentially for each tap. Each of these curves represents an exponential type of grid voltage decay between firing instants.

It can be shown that the following relationship holds:

$$V_F = V_T \left(1 + \frac{\Delta m}{m} \right)$$

where

m = "virtual" specific mass of ions which may be recorded at firing instant.

Δm = "virtual" specific mass at firing instant subtracted from the "virtual" specific mass corresponding to the next firing instant.

V_T = component of firing threshold voltage which exists between the rotary contact and ground.

V_F = component of grid bias existing between the rotary tap and ground immediately after the rotary contact has moved to the next tap in sequence.

The grid bias curve corresponding to the sequence of events occurring while ions of specific mass 10 to 46 are being recorded are shown in Fig. 4.

In the explanation given hereinabove, it has been assumed that the ion accelerating voltage decays as an exponential function of time during the recording. The firing instants and the intervals between them are determined by the rate of decay. If the rate of decay varies during the recording, the time intervals between firing instants vary in a corresponding manner. For example, if the rate of voltage decay is less for specific masses of high value than it is for those of low value, the time intervals between firing instants will be longer than those indicated in Fig. 4.

The mass marker circuit shown in Fig. 2 includes a plurality of coupled three-position switches 65, 66, 67. Position 1 on each switch is "off" position. Switch 65 is connected in the power line when on positions 2 and 3. Switch 66

if off in both positions 1 and 2, but in position 3 completes the circuit of the lower contacts of the control relay. In positions 2 and 3, the switch 67 connects the anode battery 49 to the amplifier tubes of the D. C. amplifier.

The three coupled switches are thrown simultaneously from a common control lever, respectively, to positions 1, 2 or 3. When the coupled switches are in position 1, the circuits including the switches are open. In position 2, power is supplied to the filaments of the D. C. amplifier and the other electrodes of the D. C. amplifier tubes. In this position power is also available to the panel light and marker light through a transformer if the upper contacts of the control relay should be closed. In position 3, the connections between the lower contacts of the control relay and the stepping coil of the rotary relay, and the coil of the pulsing relay are completed.

An auxiliary push button switch 68 is connected in series with switch 65 and the power lines which supply power to the reset coil 47 of the rotary relay.

Of course there may be an excess voltage over that required to just cause the rotary arm to move to the tap. However, if the voltage is such that the rotary arm just moves to a tap, that is so that there is no excess bias over the firing grid bias, the mass marker will indicate the specific mass of ions which can be detected when the aforesaid constant voltage is applied to the potential divider.

I claim:

1. In a mass spectrometer provided with an analyzer, in which a heterogeneous mixture of ions of different specific charge are projected as a beam by an electrical potential and separated into a plurality of beams of ions, each of the separated beams being composed of ions of the same specific mass, an ion collector, and a beam sweeper for sweeping the plurality of ion beams successively over and in contact with the collector by causing said potential to decay gradually, the combination which comprises a recording galvanometer for recording separately a series of currents collected from the successive beams, and a mass indicator operatively associated with the beam sweeper for indicating, simultaneously with the recording of each current, the specific mass of the ions from which that current was derived.

2. In a mass spectrometer provided with means for converting molecules into ions, a plurality of spaced electrodes for applying a potential upon the ions to propel them in a beam and an analyzer wherein the beam of ions under the influence of a field may be separated into a plurality of ion beams of different specific mass, each beam being composed of ions of the same specific mass, the combination which comprises an ion collector, a

beam sweeper which causes said potential to decay automatically thus causing the separated ion beams to sweep successively over and impinge upon the collector, a galvanometer connected to the collector for indicating successively the currents collected from the successive beams, and a mass indicator operatively associated with and actuated by the beam sweeper for indicating, simultaneously with the indication of each current, the specific charge of the ions of the collected beam from which that current is derived.

3. In a mass spectrometer provided with means for converting molecules into ions, a plurality of spaced electrodes for impressing a potential upon the ions to propel them in a heterogeneous ion beam, an analyzer wherein said beam is propelled, and means for producing a field in the analyzer to separate said beam into a plurality of homogeneous beams composed of ions of different specific masses, the combination which comprises an ion collector, a beam sweeper connected to the electrodes for progressively decreasing the potential impressed thereby on the ions so that the path of the plurality of ion beams is altered and they sweep successively over and impinge upon the collector, a galvanometer connected to the collector for indicating successively the currents collected from the successive beams, and a mass indicator operatively associated with and actuated by the beam sweeper for indicating simultaneously with the indication of each current, the specific mass of the ions of the collected beam from which that current is derived.

4. In a mass spectrometer provided with means for converting molecules into ions, at least three spaced electrodes for impressing a potential upon the ions to propel them as a heterogeneous ion beam, an analyzer wherein said beam is propelled, and means for separating said beam in the analyzer into a plurality of homogeneous beams composed of ions of different specific masses, the combination which comprises an ion collector, a beam sweeper for altering the potential applied to the electrodes to cause the homogeneous ion beams to sweep successively over and in contact with the collector, a potential divider for distributing the potential supplied by the beam sweeper between the electrodes, a galvanometer connected to the collector for indicating successively the currents collected from the successive beams, and a mass indicator connected to the beam sweeper through the potential divider and actuated by the sweeper, for indicating simultaneously with the indication of each current the specific mass of the collected beam from which that current is derived.

ROBERT V. LANGMUIR.
